UNITED STATES PATENT OFFICE

2,573,918

DEVICE FOR DISPENSING MEDICAMENTS

Robert Ellis McCuiston, Greensboro, N. C., assignor to Vick Chemical Company, a corporation of Delaware

Application November 5, 1949, Serial No. 125,799

3 Claims. (Cl. 128—206)

1

This invention relates to a device for the administration of medicaments, particularly the administration by inhalation, insufflation or atomization of powdered or liquid medicaments.

The use of powdered or liquid medicinal agents in inhalation and insufflation therapy, and, in particular, the use of antibacterial or antibiotic agents, is becoming increasingly widespread. However, the problem of simple and efficient application, especially the uniform distribution of the medicinal agent over the area to be treated, has not been satisfactorily overcome. For example, the inhalators presently used for administration of penicillin by inhalation are inefficient.

The present invention provides a device which, dispenses a powder or a liquid agent into a stream of gas to become entrained therein by the centrifugal force resulting from the rotation of a rotatable container for said material which is an internal part of the device and which rotatable container is caused to rotate by the action of the stream of gas thereon. The entrained medicinal agent is carried along in the stream of gas into or onto the body cavity or surface to which the stream of gas is directed.

The device includes the following essential parts: (1) a basket type container in which the medicinal agent is carried in the shallow cup-like top surface thereof and which is formed with a series of notched fins as an integral part of the lower basket body circumferential surface; (2) a cover which fits over the top of said basket-type container and which has a series of peripheral holes that are adjacent to the inner edge of the rim of the cup-shaped top surface of the basket when the cover is in place; (3) a body portion which is comprised of (a) a top piece having a passageway therethrough and usually tapered at the applicable end to allow insertion into a body cavity and (b) a bottom piece forming the base of the device either the top piece or the bottom piece being skirted, so that when assembled, the two form a hollow cylinder, the wall of which is the skirt, this cylinder accommodating the basket and cover assembly, the bottom piece having a passageway therethrough at such an angle that the inner opening of the passageway is close to the wall of said cylinder; and (4) bearing means including bearings and bearing points connecting the upper and lower plane surfaces of the basket and cup assembly and the corresponding surfaces of the chamber so that the basket and cup assembly are free to rotate within the chamber formed in the body portion.

2

The invention will be further described with reference to the accompanying drawing in which:

Fig. 1 is a view in side elevation of a device which embodies the invention partly in section;

Fig. 2 is a cross sectional view taken along line 2—2, Fig. 1;

Fig. 3 is a cross sectional view taken along line 3—3 of Fig. 1; and

Fig. 4 is a cross sectional view taken along line 4—4 of Fig. 1.

The illustrated choice has a top piece 1 having a passageway 2, a tapered bearing 3, and milled ribs 4; a bottom piece 5, the cylindrical side 6 of which fits over the base of the top piece 1 forming the chamber 7. The base of this bottom piece 5 includes a passageway 8 which opens into the chamber 7 close to the cylindrical wall 6 and which connects with a counterbored hole 9 extending into the bottom piece 5 from the bottom surface thereof, a bearing point 10, and milled ribs 11 which, together with milled ribs 4 on the top piece, facilitate assembling and taking apart the body portion.

25 The basket 12 fits into the chamber 7 when the device is assembled. The basket 12 has a tapered bearing 13 which fits into bearing point 10 in the bottom piece 5, a series of notched fins 14 positioned around its lower circumferential surface and a cup-shaped top surface 15. A cover 16 fits over the top of basket 12 forming the shallow cup-like chamber 17 which holds the powdered or liquid medicinal agent to be dispensed. The cover 16 is provided with peripheral holes 18, adjacent to the inner edge of the rim of the cup-shaped top surface 15 of the basket 12 and a central hole 19 which provides a bearing point for the tapered bearing 3 of the top piece 1.

30 The device is assembled by placing the basket 12 and cover 16 assembly containing the medicament to be administered into the bottom piece 5 of the body portion with the basket bearing 13 in the bearing point 10 of the bottom piece 5, and then inserting the top piece 1 into the bottom piece so that the tapered bearing 3 of the top piece fits into the bearing point 19 in the cover 16. So assembled the device is ready for use.

35 In use, a stream of air is forced through the device by drawing air through the top passageway by means of the nose or mouth as in inhalation or by blowing air or gas through the bottom passageway by means of a bulb or pressure tank attached to the connection provided by counterbored hole 9 as in insufflation or atomization.

40 The stream of gas or air entering the passageway

55

The stream of gas or air entering the passageway

8 from the bottom of the device is directed against the series of notched fins 14 and causes the basket 12 and cap 16 assembly to rotate at high velocity. The centrifugal force produced by the rotation of the basket and cover assembly forces the contained medicament to the outer edge of the cup-shaped top surface 15 of the basket and then out of the peripheral holes 18 in the cover 16. As the material emerges from the holes 18 in the cap it is entrained in the air or gas stream passing through the chamber 7 and then carried through passageway 2 in the top piece 1 to the surface or area or into the body cavity undergoing treatment.

When a bulb or pressure tank is to be used in conjunction with the device it may be easily connected to the counterbored hole 9 provided in the base of the device by a piece of rubber tubing or other similar means. Any bulb or the like for producing a stream of gas through the device should be provided of such construction that the inflation of the bulb does not draw air through the device.

By providing separate covers with different sized peripheral holes powders of varied particle size and liquids of various densities may be used with the device and the rate at which these agents are dispensed into the entrained air stream may thereby be controlled.

The basket and cover assembly may be used as a convenient and efficacious packaging medium for dosages of medicaments. When used as a packaging medium the basket and cover assembly may be discarded after administration of the medicinal agent, while the body portion of the device is retained for use with a new basket and cover assembly containing the prescribed medicinal agent. The basket and cover assembly, with the medicinal agent in it, may be individually packaged (sterile, if appropriate) for distribution. This convenient means for marketing dosages of any particular medicament eliminates handling of the medicament by the user and, in addition, assures that a cover with proper size peripheral holes is being used with each particular medicament.

In addition to the usefulness of this device in inhalation therapy, as with penicillin, the device is useful in insufflation and atomization administration of other medicinal agents.

Thus for human patients the device may be used for oral or intranasal inhalation or insufflation or the administration to the respiratory tract of any of or mixtures of the following:

1. Bacterial vaccines.
2. Sinusitis vaccines.
3. Antihistaminic agents.
4. Vasoconstrictors.
5. Antibacterial or antibiotic agents.
6. Antiasthmatic agents (such as bronchodilators).

The device may be used for insufflation into the ear of humans or animals of medicaments such as an antibacterial agent or anesthetic agent.

The device may be used for treatment of vaginal conditions such as trichomoniasis, vaginitis or cervicitis, or diseases such as gonorrhea by the

insufflation of a medicinal agent into the vagina, or for the application of a contraceptive.

For animals the device may be used for oral, intranasal, or uterine insufflation of appropriate medicaments.

The device may be used for the atomization spraying of liquids or the insufflation of powders to external body surfaces.

The above mentioned uses and usable agents are given as examples and are not meant to limit the uses for which the device is adapted.

I claim:

1. An assembly including a bottom element having a concave upper surface forming a cup-like depression therein, peripherally positioned fins on said element adapted to be impelled by a flowing fluid medium thereby to impart rotational movement to said element, and a centrally positioned first bearing means on the lower surface thereof, and a cover for said element having peripherally disposed openings and a centrally positioned second bearing means, said assembly being adapted to contain, in the cup-like depression and under the cover, a material of such nature as to be dispersible in a gas stream.

2. An assembly including a base and a top fitted one within the other to form a hollow cylinder, both the upper inner surface of the base and the lower, inner surface of the top being provided with centrally positioned bearing means adapted for the rotational mounting of a container, the base having a hole leading from the outside to the inside of the cylinder and opening into the inside of the cylinder near the periphery thereof and at an angle to the axis of the cylinder, and the top having a hole leading from the interior of the cylinder to its upper surface.

3. An assembly including an outer assembly having a base and a top fitted one within the other to form a hollow cylinder, both the upper, inner surface of the base and the lower, inner surface of the top being provided with centrally positioned bearing means, the base having a hole leading from the outside to the inside of the cylinder and opening into the inside of the cylinder near the periphery thereof and at an angle to the axis of the cylinder, and the top having a hole leading from the interior of the cylinder to its upper surface; and an inner assembly rotatably mounted within said hollow cylinder on the said bearing means, said inner assembly including a bottom element having a concave upper surface forming a cup-like depression therein, peripherally positioned fins on said element adapted to be impelled by a flowing fluid medium thereby to impart rotational movement to said element, and a cover for said element having peripherally disposed openings.
